UNITED STATES PATENT OFFICE.

HENRY H. FEFELL, OF DAYTON, OHIO.

COMBINED CHAIN AND LOCK STITCH.

1,227,045.

Specification of Letters Patent. Patented May 22, 1917.

Application filed March 9, 1916. Serial No. 83,121.

To all whom it may concern:

Be it known that I, HENRY H. FEFELL, a citizen of the United States, residing at Dayton, in the county of Montgomery and State of Ohio, have invented certain new and useful Improvements in Combined Chain and Lock Stitches; and I do declare the following to be a full, clear, and exact description of the invention, such as will enable others skilled in the art to which it appertains to make and use the same.

My invention relates to improvements in stitching and has for its object to provide a combined chain and lock stitch which may be formed by machines without the use of bobbins, the chain stitch being formed of one thread, while an additional thread is provided for locking the loops or links of the chain.

With the foregoing general object in view, the invention resides in the method of forming the improved stitch as well as in the completed stitch, both method and article being illustrated fully in the accompanying drawing which constitutes a part of this application and in which:

Figures 1 to 6 are diagrams showing the numerous steps in forming the improved stitch by machine operations;

Fig. 7 is a top view of a portion of the completed stitching;

Fig. 8 is a bottom view thereof; and

Fig. 9 is a sectional view of the material showing the stitching in elevation, this section being taken approximately on the line 9—9 of Fig. 7.

In the accompanying drawing, the numerals 1 and 2 represent a pair of vertically moving needles which are spaced apart in the direction in which the material to be stitched travels, the lower end of the needle 1 being disposed below that of the needle 2 for a reason to be set forth.

Coöoperating with the needles 1 and 2 in forming the improved stitch, is a looper 4 which will be disposed beneath the work rest of the machine as indicated in the drawings, said looper and the two needles being operated in synchronism by any preferred means which constitutes no part of the present invention. It is essential, however, that the looper 4 be provided with an elongated head 5 which is moved in close proximity to the path of the needles, said head having therein a slot 6 which opens through

one of its ends and which extends in the direction of travel of the head.

In forming the stitch with a mechanism such as that described, the needles 1 and 2 will be threaded with independent threads 9 and 10 which may obviously be of different colors if this should be desirable. The material 3 is now placed beneath the needles as shown in Fig. 1 and the machine set in operation. This moves both needles 60 downwardly simultaneously and thus forms a long loop 9^a of the thread 9 and a short loop 10^a of the thread 10, the first named loop being longer than the other, due to the difference in length of the two needles. The 65 looper 4 which has now moved to the position shown in Fig. 2 travels to the left with the result that the short loop 10^a will be received in the slot 6, said short loop being now carried through the long loop 9^a as shown in 70 Fig. 4. While the looper 4 is moving in this manner, the needles 1 and 2 have again risen and the material 3 has been advanced a predetermined amount. By the time the needles 75 again move downwardly, the looper 4 starts 80 to the right as shown in Fig. 5.

On the second downward travel of the needles, the previously formed long loop 9^a will be pulled tightly around 10^a as shown in Fig. 6, and a second short loop 10^a will be 85 formed of the thread 10, this loop being carried through the previously formed loop 10^a by the needle 2 in position to be received in the slot 6 of the looper in order that it may be taken through a second long loop 9^a 90 which is formed of the thread 9 simultaneously with the formation of the last short loop 10^a. The operation above described will now be automatically repeated, this operation taking place successively as long as 95 the machine is in use.

The shoulder 7 serves to engage the end of the numerous loops of the thread 10 as the looper 4 travels toward the right, and thus said loops will be opened sufficiently 100 to readily allow the needle 2 to pass therethrough.

When using the improved stitch, no shuttle or bobbin is necessary, and it will be obvious that the invention therefore effects a 105 great saving of time in that the operation of the machine need not be suspended as is the case with most types of sewing machines while the supply of thread on the bobbin is being replenished. It is to be un- 110

derstood, however, that the two threads 9 and 10 will be passed through the usual or any other preferred type of tension device in order that the downward movements of the needles may tighten the loops previously made, said threads being unwound from appropriate spools or reels.

The complete stitch formed by the method above described is shown in Figs. 7, 8 and 10, from which figures it will be seen that the interengaging loops 10^a of the thread 10, which loops form the common type of chain stitch, are effectively locked by the transverse loops 9^a of the thread 9. Furthermore, it is to be observed that a very neat seam will be provided, since on the exposed side thereof, the portions of both threads 9 and 10 between the loops of these threads lie parallel to each other.

From the foregoing description, when taken in connection with the accompanying drawing, the method of forming the combined chain and lock stitch as well as the advantages of the complete stitch will be readily understood without requiring a more extended explanation, and it will be obvious that the specific mechanism shown in the drawing need not necessarily be used in the formation of the same.

Although in the drawing the stitches are shown projecting from the material 3, it will be obvious that by varying the tension on the threads 9 and 10, they may be more or less embedded in said material, these adjustments being made according to the character of the material being operated upon.

Copies of this patent may be obtained for five cents each, by addressing the "Commissioner of Patents, Washington, D. C."

Obviously, the loops 9^a will more effectively hold the loops 10^a against movement if they be drawn comparatively tight, although they will exert a locking action even though the tension on the threads be weak.

I claim: —

1. The method of forming a combined chain and lock stitch consisting in simultaneously passing a long loop of thread and a short loop of another thread through the material to be stitched, in carrying the short loop through the long loop, in then simultaneously passing a second long loop of the first thread and a second short loop of the second thread through the material, in passing said second short loop through the first short loop simultaneously with the last named operation, and in then carrying said second short loop through the second long loop.

2. In a combined chain and lock stitch, the combination of a piece of material, a thread having interengaging loops passing through said material, and a second thread having locking loops passing through the material and around the exposed portions of the first named loops, substantially midway the ends thereof.

In testimony whereof I have hereunto set my hand in presence of two subscribing witnesses.

HENRY H. FEFELL.
